AMPLIFIER CIRCUITS

Francis H. Shepard, Jr., Rutherford, N. J., assignor to Radio Corporation of America, a corporation of Delaware

Original application May 28, 1934, Serial No. 727,968. Divided and this application June 10, 1938, Serial No. 212,895

4 Claims. (Cl. 179—171)

This application is a division of my copending application Serial No. 727,968, filed May 28, 1934, now U. S. Patent No. 2,137,419, issued November 22, 1938.

5 The present invention relates generally to amplifiers and more particularly to so called D. C. amplifiers, of the type adapted to amplify D. C. and low frequency A. C.

For many applications it is desirable to have 10 an amplifier that will efficiently amplify small D. C. voltages. In systems heretofore known, where more than one stage of amplification is needed, D. C. amplification is not obtained easily for the reasons that either there must be separate batteries for each stage, or a set of bucking batteries for each stage, or a set of divider resistors for each stage, or again, a very high voltage source across which the various stages may be placed in series with each other, or a 15 modulator system where the D. C. is converted into A. C., amplified and then re-converted back into D. C. All of the methods mentioned above are more or less complicated and furthermore are quite critical to adjust. It is also desirable 20 to have an amplifier operating directly on raw A. C. for use with a photo tube and other industrial uses as, for instance, temperature control systems and burglar alarm systems.

The present invention may be broadly stated 25 to comprise a method and means for cascading grid controlled rectifiers to produce a D. C. amplifier system which does not necessitate cascading the necessary tube energizing voltages. The invention also contemplates a method and means 30 for correcting for variations in the supply voltage.

Broadly speaking, in the present system the negative voltage developed on the plate of a grid controlled rectifier tube connected across an A. C. 35 line is used to bias the grid of a following tube also connected across the line. The energy to be amplified is impressed across the input of the first tube and the amplified energy is available across the output of the last tube.

40 The invention will be more readily understood from the following detailed description thereof and by reference to the drawing, the single figure of which shows a preferred embodiment of the invention.

45 The drawing shows in diagrammatic form a simplified A. C. operated D. C. amplifier circuit that is self biased and compensated for line voltage variations. As in Figures 5 through 8 of my parent application conductors 5 and 6 of the 50 present case are connected to an A. C. power sup-

ply system through terminals 1 and 2. For purposes of illustration only three tubes T₅, T₆ and T₇ have been shown comprising the amplifier, however, it is to be distinctly understood that any desired number of tubes may be utilized and connected as taught by the present disclosure. The first tube T₅ includes anode, cathode and grid electrodes. One side of the cathode is connected to line 6 while the anode is connected to conductor 5 through condenser C₈. The anode is also connected to conductor 6 through two paths one of which includes the resistor R₁₀ and the other a resistor R₁₁ and a condenser C₉ in series. The D. C. input is applied across terminals 3 and 4, terminal 3 being connected to the grid 10 of T₅ while terminal 4 is connected to a point on the resistor R₁₀ by means of a variable tap 12. A condenser C₇ is connected between the connection from terminal 4 to the resistor R₁₀ and conductor 6. 15

The second tube is also shown as including anode, cathode and grid electrodes, the anode being connected to the conductor 5 through a condenser C₁₀ while one side of the cathode is connected directly to the conductor 6. The signal grid of the tube T₆ is connected to a point on the resistor R₁₁ by means of a variable tap 13. As in the case of tube T₅ the anode of tube T₆ is connected to the conductor 6 through two paths. One of these paths includes a resistor R₁₂ while the other comprises resistor R₁₃ and a condenser C₁₁ in series. The third tube of the system T₇ is also provided with anode, cathode and grid electrodes, the cathode being connected directly to the conductor 6 while the grid electrode is connected to a point intermediate resistor 13 and condenser C₁₁. The anode of tube T₇ is connected to an output terminal 11, terminal 10 shown at one end of the conductor 5 being the other output terminal of the system. It 40 is to be understood that any desired utilizing system may be connected across the output terminals 10 and 11.

45 For a proper understanding of the operation of the system shown in the drawing, attention is directed to the curve sheets shown in Figures 1 and 2 of my parent application. It will be noted that the load line OC starts from zero as there is no D. C. supply in the circuit shown in the present application. The plate voltage will 50 always be negative as shown by the intersections with the triode rectification curves. The actual value of D. C. plate voltage with a constant A. C. voltage on the plate will vary with the grid bias. This is shown by observing the intersections of 55

the constant A. C. lines with the D. C. load line in Figures 1 and 2 of the parent case.

In normal operation, considering the tube T_5 , the anode will assume a highly negative average D. C. potential due to the rectifying action of the tube. This potential, for best amplification, will be too high a value to use directly for self-bias. However, since the load resistor is returned to ground or zero potential, a slider may be placed on 10 this resistor to obtain any average D. C. voltage from zero to the average D. C. potential of the plate. It is possible in some particular instance that the D. C. potential may be in the order of -80 volts.

15 If -4 volts is the normal bias for the tube in this circuit, the slider is adjusted along the load resistor R_{10} until a potential of -4 volts is reached. Condenser C_7 is used as a filter to bypass the A. C. on the top portion of the divider resistor R_{10} . This will keep the A. C. off the grid of the tube T_5 . If the normal bias is -4 volts, when the plate potential is -80 volts, the slider will be set approximately 1/20 of the way up the load resistor R_{10} and the degeneration due 20 to the self-bias will be one part in 20, times the actual realized voltage gain. It should be understood, of course, that the values given above are approximate values that can be expected in normal operation of the system.

30 The potentiometer R_{11} as far as D. C. is concerned is merely a resistor of negligible value in series with the grid of tube T_6 . Condensers C_{10} and C_{11} have no effect on the D. C. voltage, however, potentiometer R_{11} as far as A. C. is concerned will act as a voltage divider resistor across the line. Condensers C_8 and C_9 have negligible impedance to A. C. The instantaneous potential on the grid of tube T_6 is the sum of the D. C. voltage on the plate of tube T_5 and the instantaneous value of A. C. at the point to which the slider 35 $\mathfrak{13}$ is set on the resistor R_{11} . During the part of the cycle that the tube T_6 is conducting the instantaneous A. C. voltage applied to the grid of tube T_6 is in such a direction as to oppose the normal D. C. bias supplied by the plate of the 40 vacuum tube T_5 .

Thus, the grid during the conducting part of the cycle will be less negative than the normal bias and will be of such a value that the grid 50 of the tube T_6 will be at a suitable operating potential.

Suppose that the A. C. line voltage, that is, the A. C. voltage on the anode is increased it can be seen from the rectification curves in Figures 1 and 2 that the negative plate potential will increase. This will cause the normal grid bias of tube T_6 to become more negative. However, increasing the A. C. line voltage would also cause an increase in the superimposed A. C. on the grid 55 on the tube T_6 and this will tend to make the grid more positive during the operating part of the cycle. Since the two above mentioned effects can be made to oppose each other the effects of line voltage variations may be nullified. Compensation adjustment is made by varying the A. C. voltage on the grid of tube T_6 by adjusting the slider $\mathfrak{13}$ on the potentiometer R_{11} . As previously stated, it is possible to obtain over compensation, hence, it is possible to perform all the 60 necessary compensation for several stages in the one stage. It is also possible as previously pointed out to accomplish compensation for the effects of filament voltage variations. The explanation for filament compensation in the circuit is similar 70 to that given in the parent application in connection

with the description of curve sheet shown in Figure 4 thereof.

In the system shown in the present case the slider $\mathfrak{13}$ should be adjusted along the resistor R_{11} so that the grid of the tube T_6 swings into the 5 operating range of the tube but never swings positive with respect to the cathode.

In practice it has been found that the values of none of the resistances and condensers used are critical. In one of a number of practical embodiments of the invention, and in particular one that followed the diagram shown in Fig. 8 of the parent case a 2000 ohms resistor was used for the A. C. line shunt while the plate resistances were each one megohm, the grid resistors two megohms 15 and the condensers 0.1 mmf.

While the invention has been described by certain particular embodiments, it is to be understood that the principles underlying the invention may be carried out in many forms without departing from the spirit of the invention, and no limitations upon the invention are intended other than those imposed by the scope of the appended claims.

I claim:

1. In a direct current energy amplifier, an electronic rectifier tube provided with an anode, a cathode and a control electrode, a pair of line conductors adapted to be connected to a source of alternating current, means including a condenser for connecting the anode of said tube to one of said line conductors, a pair of parallel paths for connecting the anode to the other line conductor, one of said paths including a resistor element, the other thereof including a resistor element and a condenser in series, a connection between said other conductor and the cathode of the tube, an input circuit for said tube including a pair of terminals for connecting the input circuit to a source of energy to be amplified, one of said terminals being connected to the grid of the tube while the other thereof is variably disposed on the first named resistor element, a condenser shunted between the connection from the last named terminal to the resistor element and said other conductor, a second electronic tube provided with anode, cathode, and grid electrodes, a connection from the anode of said second tube to said other conductor including a resistor element, means for variably connecting the grid of 40 said second tube to a point on said second named resistor element, means including a reactance device for connecting the anode of said second tube to the first named conductor and a connection from the cathode of the second tube to the 50 other line conductor, said second tube having potentials impressed upon the grid thereof determined in accordance with the amount of current rectified by said first tube.

2. In a relay circuit, a space discharge device 60 including an anode and a cathode adapted to be connected respectively to opposite conductors of an alternating current power supply line to thereby impress alternating current voltage between the anode and cathode of the discharge tube, a control grid for said tube, a path conductive to direct current and including a resistor connected between the anode and cathode of said tube, an alternating current path including a resistor and a condenser in series, connected in 65 parallel with said first named resistor, a pair of input terminals for said amplifier, one of said input terminals being connected to said control grid, the other thereof being connected to an intermediate point of the first named resistor, 70

and a utilizing circuit connected between a point of the second named resistor and said cathode.

3. An arrangement as described in the next preceding claim characterized by that the utilizing circuit comprises a second space discharge device having an anode and a cathode connected respectively to the opposite conductors of the electrical power supply line, and a grid electrode connected to a point of the resistor of the 10 alternating current circuit.

4. In a relay circuit, a pair of line conductors adapted to be connected to an alternating current network, a first electronic tube having an anode, a cathode and a grid electrode, a connection 15 including a condenser between the anode and one of said line conductors, means connecting the cathode to the other line conductor, a resistor connected between the anode and the last named line conductor, a second connection 20 between the anode and said last named line conductor including a resistor and a condenser in series, a pair of input terminals one thereof being connected to the grid electrode and the

other to the point of the first named resistor, a second electronic tube including an anode connected to the first named line conductor through a condenser, a cathode connected to the second named line conductor and a grid electrode connected to a point of the second named resistor, means for connecting the last named anode to the second named line conductor including a resistor, a second connection between the last named anode and said second named line conductor including a resistor and a condenser in series, a third electronic tube including an anode, a cathode and a grid electrode, a pair of output terminals, means for connecting one of said output terminals to said first named line 15 conductor and the other output terminal to the last named anode, means for connecting the last named cathode to the second named line conductor and a connection between the grid of said third electronic tube and a point of the last 20 named resistor.
